(57) **CLAIM**

The ornamental design for a light, as shown and described.

DESCRIPTION

FIG. 1 is a front elevational view of a light showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a third perspective view thereof;

FIG. 10 is a fourth perspective view thereof;

FIG. 11 is an enlarged view of FIG. 3; and,

FIG. 12 is an enlarged view of FIG. 4.

The break lines in the figures indicate that the appearance of any portion of the light between the break lines forms no part of the claimed design.
